UNITED STATES PATENT OFFICE

CLARENCE E. REED, OF WICHITA, KANSAS, ASSIGNOR TO CHICAGO PNEUMATIC TOOL COMPANY, OF NEW YORK, N. Y., A CORPORATION OF NEW JERSEY

DEEP WELL DRILL BIT

Application filed September 9, 1927. Serial No. 218,504.

The invention relates to a roller coring bit for deep well drilling and it consists in the features and combination and arrangement of parts hereinafter described and particularly pointed out in the claims.

In the accompanying drawings

Figure 1 is a vertical sectional view of a bit head, with the roller cutters omitted.

Fig. 2 is a bottom plan view.

Fig. 3 is a vertical sectional view of part of the head with the roller cutters in place.

Fig. 4 is a detached view of one of the spindles with its shank.

Fig. 5 shows views of the locking piece.

Fig. 6 is an end view of one of the spindles of the head.

Fig. 6a shows an exterior spindle.

Fig. 7 shows views of a bushing.

Fig. 8 shows views of a locking piece.

Fig. 9 is a plan view and Fig. 10 is a sectional view of core lifting means.

Figs. 11 and 12 are detail views relating to the core lifting means.

In these drawings the head 1 is in one piece. The opening for receiving the core is shown at

2. Surrounding this opening are the cutters. While different organizations of cutters may be employed, I desirably employ five cutters in the particular form of bit now being de-

scribed. Three of these are frusto-conical cutters and two are cylindrical cutters. As shown in Fig. 2 two of the frusto-conical cutters are to be mounted in recesses 3 in close proximity to each other on one side of the bit

35 head and the third frusto-conical cutter is to be mounted in a recess 3a widely and equally spaced apart from the members of the pair of closely set cutters. These recesses are of

substantially the same form. This third cutter in other words has its axis in a vertical plane passing through the vertical center of the drill head and midway between the pair of conical cutters first mentioned. This ar-

40 arrangement affords ample space within which to locate a pair of cylindrical cutter units, these being located at substantially opposite sides of the drill head on outwardly and downwardly extending spindles 4. As shown in the bottom plan view Fig. 2 the axes of

45 these spindles are at an angle to each other,

and said axes are convergent towards the vertical axis of the drill head. The sides of the drill head at 5 are inclined relative to each other and substantially straight, and these are in convergent relation to each other from that side of the head at which the pair of frusto conical cutters are located. 55

In other words the head viewed in bottom plan as in Fig. 2 presents a formation wider at the right hand end than at the left, and these ends are connected by convergent straight sides from which the spindles 4 project outwardly and downwardly and at right angles to the planes of said sides. This formation provides spaces between the straight 60 sides 5 of the bit head and the wall of the hole for the upflow of the flushing fluid.

The recesses in which the frusto-conical cutters are mounted are separated from the core receiving passage 2 by vertical walls such as 3b in Fig. 1. This recess is also defined by an inclined wall portion 6 extending upwardly and outwardly and forming a continuation of the outer side of the wall 3b. At the top of the wall portion 6 there is a short horizontal ceiling 6a which joins an upwardly and inwardly inclined ceiling 7 defining the outer side of said recess 3 or 3a, said ceiling 7 having a seat recess 7a therein presenting a thrust sustaining shoulder at 7b. 70

75 Connecting with this formation is a socket 8 of cylindrical form with its axis parallel with the vertical axis of the drill, said socket being reduced at 8a and connecting with a recess 9 formed in the side of the bit head to receive means for holding the shank of the roller cutter unit in place in the socket 8 as will be described.

80 The socket 8 also has communicating therewith a channel or recess 10 extending from the side face of the bit head and communicating with the seat recess 7a. The frusto roller cutter unit comprises a spindle 11 of external stepped formation as at 11, 11a, adapted to receive a frusto-conical roller 85 cutter 12 having an internal bore adapted to fit this stepped formation of the spindle.

90 The spindle is in one piece with a base portion 13 in the nature of a flange or plate adapted to fit in the seat recess 7a and with 100

its upper edge against the thrust sustaining shoulder 7b so that the stresses are distributed into the head through this base or flange member which on its outer side fits against 5 the ceiling of the seat recess.

From this base the shank 14 of the rolling cutter unit extends upwardly at an angle to the axial line of the spindle and its base which it will be observed extends at right angles to the inclined wall 7 of the recess 3 or 3a. This shank fits in the socket 8 and is formed in one piece with the base and its spindle. At the back of the base there is a hump 15, which fits in the recess or channel 10 and sustains certain strains to which the unit is subjected. As thus far described the roller cutter unit is similar in certain aspects to those described in Letters Patent issued to me July 19, 1927, and the means for securing 20 the shank of the unit in place may be similar to those shown in said patents or to that shown in the patent to F. K. Blauvelt No. 1,636,669 of the same date.

In the present form the roller cutter is 25 held on the spindle by locking piece 16 which is generally of taper form varying from a uniform shape in that its edge 16a is slightly off to one side of its axis. This member has a shank 17 to fit a recess 18 in the inner end 30 of the spindle of the roller cutter unit.

When this locking piece is seated with its shank in the spindle its shoulder 19 will bear against the outer face of the frusto conical cutter so as to hold it on the spindle. The 35 long inclined face of the lock, when the unit is in place in the head, will find a bearing against the outer face of the wall 3b, and thus the roller cutter will be held on the spindle by this locking member which is 40 merely slipped into place in the spindle and bears on the wall 3b.

This member and the frusto-conical member are assembled with the spindle so that 45 all these parts can be handled as one body by slipping the unit up into the bit head in a direction parallel with the vertical axis thereof, and despite the restricted space forming the recess 3 or 3a, it being noted that the size and relation of the parts is such 50 that the face of the locking piece may slide along the outer face of the wall 3b, and in contact therewith. The lower face of the locking piece as viewed in Fig. 3 is inclined upwardly and inwardly from a point above 55 the lower edge of the frusto-conical cutter to the horizontal plane of the lower edge of the wall 3b. This lower face of the locking piece moves over the path cut by the cylindrical cutter units 20, each of which is composed of 60 a pair of cylindrical cutters on each of the downwardly and outwardly inclined spindles 4. These spindles are integral with the head.

Each is provided intermediate of its length with flanges 4a extending in a circumferential direction in respect thereto and spaced 65

apart to form gateways 4b. A bushing 21 of cylindrical form is adapted to be slipped onto the spindle having flanges 21a and gateways complementary to the gateways and flanges of the spindle so that the sleeve or bushing can be slipped on the spindle and when turned its flanges will engage back of the flanges on the spindle, and then by inserting a locking member 24 with its prongs 70 in the aligning gates and a cotter or other pin 75 or fastening through the hole 22 and notches 22a, the bushing will be held from turning and as this bushing has a flange 23 at its outer edge the roller cutters 20 will be held in proper relation to the head to do the cutting. This bushing and mounting are similar to that disclosed in Letters Patent of the United States granted to me July 19, 1927, Serial No. 1,636,663.

The bushing or retaining sleeve is slabbed off at 24a in the vertical plane of the outermost corner or edge of the cylindrical roller cutter so that this face will be within the clearance cut by the outermost element of the cutters. 80

The core lifting means may assume various forms. As one form I show in Figs. 9, 10, 11 and 12 a body consisting of a downwardly tapered spring steel ring 25, split at 26 at an angle of 45° so that under pressure of 85 the entering core the lifter will move upwardly within the conical bore 27 of the head and will expand. To the spring steel ring are fixed by welding or riveting segmental toothed slips 28, spaced apart. Between the 90 spring steel ring or body and the slips are mounted wings 29 each of which is made of two strips of spring steel welded together. The wings are arc shape and their free ends form substantially resilient fingers which 95 contact with the core and steady the core lifter as the core enters and this contact serves to assist in making the toothed grips or slips engage the core as the bit head is lifted, so that the latter will lift the core out of 100 the bore hole.

The recesses 3 in which the closely spaced frusto-conical cutters are located communicate with each other so that flushing fluid 105 can have free access to the cutters.

Any suitable ports may be employed for directing the flushing fluid.

It will be observed that the recesses in which the frusto-conical rollers are located are relatively small, presenting a limited or confined space for receiving the cutters, and hence my roller cutter unit consisting of the spindle, the shank at an angle thereto enables the cutter unit to be placed or removed from this confined space by a movement substantially parallel with the vertical axis of the drill head, and as the inner wall of this recess as at 3b is substantially vertical, the movement of the unit in placing or removing it takes place in a direction parallel with said 115 120 125 130

wall. The locking block 16 constitutes a simple and effective means for locking the roller cutter to its spindle, but I do not limit myself in this particular. It is of importance, however, that the roller cutter be assembled with the spindle or bearing member outside of the head so as to be handled as one body therewith in placing it in the head or removing it therefrom.

I claim:

1. A coring bit for deep well drilling apparatus comprising a one piece head having a core receiving opening, a recess disposed to one side of the core opening and separated therefrom by a wall portion of said head, said recess having an upwardly and inwardly inclined outer wall, and connecting with a socket in the head, and a roller cutter unit comprising a spindle to extend substantially at right angles to said inclined wall and having a shank extending upwardly into said socket at an angle to the axis of the spindle and substantially parallel with the vertical axis of the drill head, said spindle having a roller cutter mounted thereon to be handled therewith as one body in inserting or removing the roller cutter unit, said separating wall portion and inclined outer wall forming a pocket in which the roller cutter is housed and said separating wall portion providing a support for the roller cutter unit, substantially as described.

2. In combination in a deep well drilling bit, a head having a recess in its lower end, a roller cutter unit composed of a spindle and a shank with a roller cutter on the spindle, means to hold the said unit to the head with its shank in a socket of the head, and means for retaining the roller cutter on the spindle consisting of a member removably held by the spindle and bearing on the wall of the recess, substantially as described.

3. A deep well drilling bit according to claim 2 in which the retaining member for the roller cutter has a shank seated in a socket in the end of the spindle.

4. A deep well drilling bit according to claim 2 in which the retaining member for the roller cutter is of taper form, bearing on the wall of the recess of the head, substantially as described.

5. A deep well drill bit according to claim 1 in which the wall portion between the core opening and the recess has a vertical surface defining the inner boundary of said recess, a member detachably connected with the spindle holds the roller cutter thereon and bears on the said vertical surface, substantially as described.

6. A deep well drilling bit according to claim 2 in which the member for holding the cutter on the spindle consists of a member having its axis substantially coinciding with the axis of the spindle which inclines downwardly and inwardly from the outer upward-

ly and inwardly inclining wall of the recess, substantially as described.

7. A roller cutter unit for earth boring bit heads comprising a spindle and shank at an angle to each other, a roller cutter on the spindle, and a member to hold the roller cutter on the spindle, said member being detachable from the spindle at the exposed end thereof, and when in place overlapping the roller cutter, and adapted to be retained in place on the spindle by contact with a portion of the bit head to which the unit is to be removably attached, said member, together with the roller cutter, being assembled with the spindle and its shank to be handled therewith as one body in placing the unit in or removing it from the bit head, substantially as described.

8. A unit according to claim 7 in which the holding member has a face substantially parallel with the axis of the shank of the unit, and adapted to bear on a wall of the bit head.

9. A unit according to claim 7 in which the holding member has a shank to fit a recess in the end of the spindle, substantially as described.

10. A roller cutter unit according to claim 7 in which the shank is adapted to be seated in the bit head substantially parallel with the vertical axis thereof and the axis of the spindle inclines downwardly and inwardly in respect to the axis of the shank, substantially as described.

11. A bit for deep well drilling comprising a head with a recess in its lower end defined by an inner wall extending substantially parallel with the vertical axis of the head, and an outer wall inclining upwardly and inwardly towards said vertical axis, said bit head having a socket connecting with said recess and extending substantially parallel with the vertical axis of the drill head and a roller cutter unit composed of a spindle to extend at right angles inwardly and downwardly from the inclined wall of the recess, an integral shank portion to extend up into the said socket, and a roller cutter on the spindle, means for holding the said unit movably to the head, said unit being movable in placing or removal in a direction substantially parallel with the inner wall of the recess, and a member detachably connected with the spindle and bearing on the vertical wall of the recess to hold the roller cutter on the spindle.

12. A roller cutter unit according to claim 7 in which there is a base flange at the junction of the spindle and shank extending in a plane at right angles to the axis of the spindle, and said detachable member has a flat substantially vertical face which is convergent upwardly with the plane in which the base flange lies.

13. In combination in a rotary bit for deep well drilling, a head having a recess off cen-

ter, defined by an upwardly and inwardly inclined wall on its outer side and by an upwardly extending wall on its inner side, said bit head having a substantially vertical socket communicating with said recess, a roller cutter unit comprising a spindle and a shank at an angle to each other, said shank being adapted to fit into said vertical socket, and said spindle being adapted to extend inwardly substantially at right angles to the outer inclined wall of the recess, a roller cutter mounted on said spindle, and a locking piece detachably connected with the inner end of the spindle and engaging the roller cutter to hold it on the spindle, said locking piece being held in connection with the spindle by bearing on the inner wall of the recess, substantially as described.

14. In combination in a roller cutter assembly for earth boring drills a spindle having an end face extending in a plane at right angles to the spindle axis and with a socket in said end face, said spindle having a shank extending at an angle to the spindle axis to extend into a socket of the drill head parallel with the vertical axis thereof, and a member to engage the roller cutter having a shank to enter said spindle socket and a surface surrounding said shank to bear on the end face of the spindle and extend beyond the same to engage a roller cutter, and having also a flat outer face extending in a plane substantially parallel with the axis of the spindle shank to bear on a surface of the drill head to hold said member in engagement with the spindle.

15. A bit head for an earth boring core drill having an axially disposed core opening and a recess disposed laterally in respect thereto with a wall between said opening and said recess, the outer side of said wall being flat and parallel with the drill axis, the outer wall of said recess inclining downwardly and outwardly, the head having a socket extending upwardly from the inclined wall and parallel with the vertical axis of the head.

In testimony whereof, I affix my signature.
CLARENCE E. REED.
